UNITED STATES PATENT OFFICE

SIDNEY E. GORBUTT, OF PORTLAND, OREGON, ASSIGNOR TO ELECTRIC STEEL FOUNDRY COMPANY, OF PORTLAND, OREGON

SCREEN SHAKER

Application filed January 21, 1930. Serial No. 422,265.

This invention relates generally to the paper-making industry and particularly to a shaker for diaphragm screens.

The main object of this invention is to provide an improved form of screen shaker which will have several advantages over the wooden toe blocks now in common use.

The first of these advantages resides in the use of an antifriction bearing roller which 10 rides on a metal cam for the purpose of imparting the desired vibratory action to the diaphragm. The second advantage is to eliminate the wear imposed on rubber diaphragms when the shaking mechanism is not 15 accurately adjusted, which is ordinarily the case, due to the difficulty of keeping wooden parts in accurate adjustment. The third advantage is economy in time ordinarily spent in keeping the shaker mechanism in adjustment. The fourth advantage arises from 20 the use of a shaker which is easily and accurately adjustable.

I accomplish these results in the manner set forth in the specification following as 25 illustrated in the accompanying drawings, in which:

Figure 1 is a vertical transverse section through a shaker mechanism, diaphragm screen and flow box. Figure 2 is a vertical 30 section taken along the line 2-2 in Figure 1. Figure 3 is a vertical section taken along the line 3-3 in Figure 2.

Similar numbers of reference refer to similar parts throughout the several views.

Referring in detail to the drawings, there 35 is illustrated a screen box 10 on the inner sides of which are secured the strips 11 upon which rests the screen plate 12 of the perforated type such as are in common use. The box 10 rests upon a frame 13 on whose top side is secured a rubber diaphragm 14 which forms a water-tight bottom for the box 10. The frame 13 rests upon the upright standards 15 upon whose side brackets 16 is mounted a flow box 17 containing the usual 40 adjustable dam 18. The flow box 17 is connected to the box 10 by means of a flanged pipe 19 through which the stock 20 flows from the box 10 into the flow box 17.

The diaphragm 14 is held between the

boards 21 and 22 by means of the bolts 23 which pass through the spacer 24, which in turn is bolted to the spring-board 25 by means of the bolts 26. The spring-board 25 is secured to the under side of the frame 13 by means of the bolts 27.

Referring more particularly to my invention, same will be seen to consist in the shaker element itself, which includes a shaft 28 on which is keyed a three-lobed cam 29 which is partly inclosed by the housing 30 on which is mounted the arm 31 to which is secured a spring-arm 32 by means of the bolt 33. On the end of the spring-arm 32 opposite the bolt 33 is secured the horizontal portion 34 of a cam roller standard 35 to whose upright portion 36 is secured a shaker rod 37, which in turn is secured to the spacer 24 by means of the bolt 38. The rod 37 is adjustably secured to the member 36 by means of the bolts 39 which pass through the slotted openings 40 in the member 36 and through the rod 37 and also through a plate 41 whose bottom edge 42 is in turn under the rod 37. The plate 41 is provided with the laterally extending lugs 43 which are directly above the lugs 44 on the standard 35. In the lugs 44 are secured the studs 45. The threaded end 46 of each stud 45 passes through the opening 47 in its respective lug 43 on each side of which is placed a nut 48.

On the top side of the spring-arm 32 at its point of fastening to the member 34 is placed a plate 49. A bolt 50 passes through the members 32, 34 and 49 and securely holds same together. Through the members 32, 34 and 49 is also formed a free hole 51 through which passes the elongated bolt 52 whose head 53 occupies a T-slot 54 in the arm 31 which may be integral with or secured to the housing 30. On the top side of the plate 49 and surrounding the bolt 52 is a compression spring 55. Initial tension is provided for the spring 55 by means of the nuts 56.

Passing through the sides of the standard 35 is a horizontal pin 57 between which and the cam roller 58 are the anti-friction rollers 59 at the outer ends of which are placed the grease-retaining caps 60. Lubrication is

supplied to the bearing surface of the roller 58 through the fitting 61.

Before operating the device, it is necessary to adjust the shaker mechanism by means of the nuts 48 so that the mean position of the roller 58 will hold the rubber diaphragm 14 in approximately a straight plane, the vibrations caused by the cam 29 moving the rubber diaphragm 14 a slight distance to each side; that is, above and below said straight plane. The net results obtained by the use of this device, though consisting primarily in the agitation of the stock solution, consist also in providing a dependable vibrating means not susceptible to sufficient wear to cause same to hold the rubber diaphragm 14 in an injurious position. The function of the spring 55 is, of course, to hold the roller 58 into contact with the cam 29.

320 Another advantage arising from the use of the metal roller 58 instead of the usual wooden toe block resides in the fact that the cam 29 can be shaped to provide the best agitating action.

325 I claim:

330 A shaker screen having in combination a screen plate, a rubber diaphragm mounted under said screen plate, a spring board under said rubber diaphragm connected thereto, a shaker rod attached to said diaphragm, a roller adjustably mounted on the lower end of said shaker rod, a cam for operating said shaker rod in a manner to produce a vibratory action on said rubber diaphragm and spring means for urging said roller toward said cam.

SIDNEY B. GORBUTT.
